ELECTRIC SWITCH BUTTON

Wesley T. Sorenson, West Hartford, Conn., assignor to
Sorenson Lighted Controls, Inc., West Hartford, Conn.,
a corporation of Connecticut

Filed Aug. 22, 1962, Ser. No. 71,417

Term of patent 14 years

(Cl. D26—13)

FIG. 1.

FIG. 2.

FIG. 3.

FIG. 4.

FIG. 1 is a front elevational view of an electric switch button, showing my new design;

FIG. 2 is a side elevational view thereof;

FIG. 3 is a top plan view when rocked in the position shown in FIG. 2; and

FIG. 4 is a cross-sectional view taken on lines 4—4 of FIG. 1 and looking in the direction of the arrows.

The face plate shown in broken lines is for illustrative purposes only.

I claim:

The ornamental design for an electric switch button, substantially as shown and described.
